FLOATING SWIMMING POOL TOY

Olga Ann Fenar, 633 N. Taylor St., Apt. 20,
Montebello, Calif. 90460

Filed Aug. 28, 1972, Ser. No. 284,146

Term of patent 14 years

Int. Cl. D21—01

U.S. Cl. D34—15 DD

FIG. 1 is a front perspective view of a floating swimming pool toy showing my new design;

FIG. 2 is an end elevational view thereof;

FIG. 3 is a side elevational view thereof;

FIG. 4 is a top plan view thereof; and

FIG. 5 is a bottom plan view thereof.

I claim:

The ornamental design for a floating swimming pool toy, as shown.
